UNITED STATES PATENT OFFICE

MAXIMILIAN WEIL, OF NEW YORK, N. Y.

ELECTRIC SOUND REPRODUCER

Application filed October 1, 1929. Serial No. 396,508.

My present invention relates to phonograph reproducers of the electromagnetic type and is particularly concerned with the magnetic pick-up and the mechanical support and control thereof.

Among the objects of the invention are to provide a magnetic pick-up construction of simple and relatively inexpensive construction, the performance of which shall be satisfactory for discriminating audiences in the reproduction of talking pictures.

Another object is to provide an apparatus of the above type, which is not only substantially proof against sticking or "freezing" of the armature thereof to a pole piece but which shall be readily maintained in balance mechanically and electromagnetically to assure best performance.

Another object is to provide apparatus of the above type which permits of ready removal and replacement of the magnetic pick-up head, without the need for disconnecting the circuit of the amplifier with respect to the reproducer arm, and which facilitates the establishment of electric circuit with respect to said head, regardless of the mechanical tightness or looseness of the mounting connection between the arm and the pick-up head and in which repeated manipulation of the head for replacing the stylus and the like, for instance, will not result in loosening the electrical contact through which the minute currents must pass in the operation of the instrument.

A feature of the invention is the construction of magnetic pick-up head in which damping means is so disposed and correlated with the armature that it may be conveniently set by hand to assure magnetic balance with respect to the pole pieces. Preferably the damping means comprises a block of gum rubber which intimately contacts both faces of an armature vane near the extremity thereof or beyond the coil, and the rubber damper is so arranged that it may be bodily moved by manual adjustment from the exterior of the case to balance the construction.

In a preferred construction the rubber damper is disposed in a metal capsule which is itself connected by screws preferably to the

pole pieces, and the adjustment means may be a screw, threaded into the reproducer casing and having a grooved connection with the capsule so that by turning this screw, the capsule may be shifted slightly for the desired purpose.

While the condition of magnetic balance may be ascertained by noting equality in volume of sound in tapping the stylus at either side, it is desirable also to provide the case with a scanner from which the central position of the armature within the air gap between the poles may be visually ascertained.

Another feature is the arrangement of the magnetic head as a unit, easily connected mechanically and electrically with respect to the carrying arm. For this purpose it is preferred to afford a ready mechanical connection and an independent relatively loose electrical connection. Any of various mechanical connections may be used, but I prefer to plug a piloted part of the reproducer mounting bracket in the channel end of the reproducer arm and to secure the parts by appropriate screws. The electrical connection is preferably effected by the prong ends of terminal wires protruding from the pick-up case and releasably plugged in a pair of electric sockets carried by the reproducer arm. The jack sockets are connected to conductors clamped longitudinally of the arm, preferably within the channel and extend to near the opposite end from which they are electrically connected to the amplifier.

Another feature of the invention is the mounting means for the reproducer arm. This mounting means preferably comprises a base supporting a hub by means of a thrust bearing, the hub preferably having a horizontal axis upon which the reproducer arm is mounted.

In the drawings in which is shown one of various possible embodiments of the several features of the invention.

Fig. 1 is a plan view of the reproducer arm,

Fig. 2 is a view in longitudinal cross-section taken on line 2-2 of Fig. 1, with the pick-up unit in side elevation,

Figs. 3, 4, 5, 6 and 7 are respectively trans-

100

verse cross-sectional detail views on lines 3—3, 4—4, 5—5, 6—6, and 7—7 of Fig. 2.

Fig. 8 is a plan view of the magnetic pick-up illustrating the scanner device,

5 Fig. 9 is a plan view thereof on a larger scale with the cover removed,

Fig. 10 is a fragmentary sectional view on line 10—10 of Fig. 11,

10 Fig. 11 is a fragmentary sectional view on line 11—11 of Fig. 10,

Fig. 12 is a transverse sectional view on line 12—12 of Fig. 11,

15 Fig. 13 is a perspective view illustrating a preferred magnetic pole arrangement and

Fig. 14 is a perspective view of the damper unit.

Referring now to the drawings, there is shown a support base 20 of more or less conventional construction, which may be partly 20 cut away interiorly as at 21 for lightness, and has fixed axially thereof an upstanding support post 22 in a depression in the upper end of which is a ball 23 affording a thrust bearing for the carrying hub 24 on which reproducer arm A is supported. The hub 24 presents a socket 25 telescoped over the ball 23 and rod 22, and has a sleeve 26 integral with the lower end thereof, encircling the base 20 for free rotation thereabout. A screw 27 30 through the sleeve 26 rides in a peripheral groove 28 about the base to prevent these elements from coming apart.

The hub 24 has an integral lateral bracket 29 with a horizontal bore affording a bearing 35 30 for mounting the reproducer arm A. For this purpose, the arm A which is of channel shape straddles the bracket 29 laterally. Screws 31 and 32 inserted through corresponding apertures in the sides s of the channel arm are threaded at their inner ends into 40 corresponding taps 33 and 34 within the bracket 30. Set screws 35 and 36 through the lower part of the bracket 30 lock the bearing screws to the latter, so that the parts between 45 the heads h and the bracket bearing 30 afford the support bearing for the arm A. Preferably the bracket 30 is provided with an upstanding outer end 40 surmounted by a piece of felt 41 which yieldingly limits the downward movement of the pick-up unit U at the 50 outer end of the arm A.

Preferably the upper end of the hub 24 extends to a level above that of the arm A, for which purpose for the web the latter is provided with an elongated slot 42 through which the upper end of the hub protrudes.

The arm A is preferably so arranged as to be normally balanced in horizontal position, for which purpose a counter-weight 43 attached by screw 44 to one end thereof serves to counterbalance the weight of the magnetic pick-up head U secured at the other end. The counter-weight 43 is preferably disposed between the sides of the channel arm and the slot 45 for the screw 44 is elongated to permit ad-

justment of the weight for correct counter-balancing.

The pick-up head U, the detailed construction of which will be described hereinafter, has a bracket piece 47 secured to the casing by screws 48 and having integral therewith a pilot flange 49 adapted snugly to pass between the sides of the channel arm A to a limiting position determined by bead 50 on the bracket. The pilot may be held in position by a screw 51 threaded through one of the sides A of the arm and through one side of the pilot flange 49. A short screw 52 laterally of said first screw through the opposite side s of the reproducer arm and threaded into the pilot flange acts as a stop for the bias-cut lower edge 53 of the pilot to prevent pivotal movement of the pick-up head about the screw 51.

Preferably the electrical connection from the coil C of the pick-up is independent of the mechanical mount of said unit, and in the preferred embodiment quick-detachable with respect to the connection from the reproducer arm A to the amplifier (not shown). For this purpose, one of the sides s of the channel arm is preferably provided with a pair of jack sockets between the spring fingers 55 of which are releasably clamped the prong ends 56 of flexible wire leads 57 from the coil C. The screw 51 terminates short of the side of the pilot, to permit passing the leads 57 for clamping the same against pilot face 49, the screw serving as a cleat prevents dragging of said leads upon the record (not shown). As a precaution, a piece of insulating tubing 58 about the screw 51 insulates the latter from the wire leads 57.

Each of the jack sockets preferably has a bushing 59 protruding laterally from the side of the arm A, through which the prong end 56 of the wire lead is inserted, said bushing having threaded upon the inner end thereof a nut 60 which clamps the base ring 61 of the spring finger unit in position. To socket rings 61 are preferably soldered as at 62, the ends of conductors 63 and 64 respectively leading longitudinally of the arm A for connection to the amplifier (not shown).

For convenient mount of said longitudinal connectors, one or more cleats 65 are provided. These cleats are preferably curved in conformity with the curvature of a trough 66 pressed into the web of the arm A, thereby forming lateral guides 67 in which the conductors are held by the clamping pressure exerted by holding screw 71 which passes centrally through the depression 66 and clamps the cleat in place.

By the construction disclosed the arm A is freely rotatable about the base 20 as an axis and may be readily set with respect to a record of any diameter and will travel therealong as required. The arm also has limited

freedom of movement about pivot screws 31 and 32 in a longitudinal plane, so that the stylus S can adapt itself to the varying levels incurred in the playing of records.

5 The tightness or looseness of the mechanical mount of the pick-up U with respect to the arm A in no way affects the security or reliability of the electrical connection, since the latter is established through the independent leads 57.

10 To replace a magnetic pick-up unit, it is merely necessary partly or wholly to remove screws 51 and 52, to remove the prongs 56 from the spring fingers 55 and withdraw the 15 unit, for which a substitute may as conveniently be replaced. The electrical connections along the arm and from the arm to the amplifier need not be disturbed.

15 Thus repeated manipulation of the head 20 for replacing the stylus, for instance, for adjustment and the like, will not result in loosening the electrical contact between the head and the arm, which contact must remain particularly intimate to assure passage 25 of the infinitesimal currents utilized in the operation of the instrument.

20 In Figs. 8 to 13 is shown a preferred form 25 of magnetic pick-up unit, which while preferably used on the reproducing arm and support above described may be used to advantage in other relations. The magnetic pick-up unit comprises a more or less conventional case U within which is mounted a horse-shoe magnet 70 held in place by a plate 71, secured by screws 72 threaded to the back of 30 the casing U. The horse-shoe magnet has associated therewith, pole pieces 73 and 74 of the usual magnetic metal, which in turn are secured to the case by bolts 75 and 76. 35 The pole pieces have notches 77 at their inner faces, determining a case for the electromagnetic coil C and grooves 77' along which the wax used for securing the coil in place will spread. Through the coil extends the 40 armature 78 which preferably has integral gudgeon pins 79 encircled by rubber sleeves 45 disposed in corresponding cylindrical bearing support 81 between contiguous edges at the lower part of the pole pieces. The 50 armature has the usual socket 82 at its lower end for the stylus S which is retained in position by the usual set screw 83.

55 In the plane of the gudgeon pins, the armature is preferably provided with an integral flat vane 84 extending through the air gap 85 between the ledges 86 and 87 of the two pole pieces.

60 A damping construction is intimately associated with the upper end of the vane which protrudes above the air-gap. This construction is preferably a unit comprising a capsule including a sheet metal base piece affording a socket 90 lodging a rectangular block 91 therein, of resilient plastic material, 65 preferably gum rubber, longitudinally slit

for snugly accommodating the upper end of the armature vane 84. The base of socket 90 has an opening 94 through which vane 84 extends with sufficient clearance to prevent any engagement between said metal parts. The capsule also includes a cover tray 92 of sheet metal, the peripheral area of which rests upon the ends 90' of the base 90. The cover may have a central opening 94 smaller than the rubber block 91 to clamp the 70 periphery of the latter. 75

75 Ends 90' support the capsule by resting upon the pole pieces, the damper extending therefrom downward into depression 88 formed by corresponding notches in the upper faces of the pole pieces. The lower face of socket 90 clears the pole piece structure therebelow as shown and the rubber is free from contact with the pole pieces at all times. 80

80 The lateral flanges 95 of the cover straddle the pole pieces, and the end flanges 96 thereof extend into notches 97 in the upper faces of the pole pieces. The rim of the damper capsule is preferably slidably clamped against the tops of the respective pole pieces illustratively by screws 98, three 90 in number, two through the pole pieces 73, and one through piece 74 midway between the lateral edges thereof. Both the socket piece and the cover piece have elongated slots 99 for the screws, to permit the adjustment presently to be described. The cover flange 96 is notched at 100 to straddle a groove 101 about a screw 102 threaded through pole piece 73 and having a fillister head 103 accessible from the lateral wall of the casing U. A washer 104 of gasket material is preferably disposed under the head of the screw and a coil spring 105 encircling the screw and reacting against the pole piece 73 and the casing U normally maintains the screw in tight relation. 100

100 Preferably the case is provided with a scanner opening 110 which may be covered by a sheet 110' of celluloid or other transparent material. The scanner opening is directly in front of the magnetic air gap. The scanner opening has lateral extensions 111 which facilitate entry of light, readily reflected by the smooth metal parts within. By use of the scanner, geometrical centering of the armature may be visually ascertained. 110

110 By my invention, the armature may be readily set for and maintained in perfectly balanced condition, with a degree of precision corresponding to that attainable in a laboratory. For this purpose, it is preferred to balance or calibrate the unit from time to time, preferably about as often as a stringed instrument is tuned by a musician, usually preparatory to each performance. 120

120 Calibration to correct balanced position is accomplished by adjusting movement of the screw 102, with the aid of a screw driver or 125 130

coin. By this movement the floating damper capsule is displaced longitudinally in the direction of armature movement determined by the elongated slots 99, for bodily movement therewith of the gum rubber damper and with 5 the latter of the armature. No strain is applied to the rubber in any such adjustment as might be the case were it attempted for this purpose to slide the rubber over the fixed pole pieces or any other fixed metal part. The latter operation might result in the rubber buckling rather than gliding with respect to the metallic surface, and in subsequently restoring itself, the rubber would again displace the 10 armature from balanced position. By the calibrating action according to my invention, 15 not only is the quality of performance maintained at its best, but incidentally the inoperativeness due to "freezing" is obviated.

20 Inasmuch as the magnet used in apparatus of the character described is quite powerful, it is desirable to seal all openings in the case through which small paramagnetic particles might be attracted and caused to impair the 25 action of the apparatus. For this purpose the socket 82 is encircled by a rubber bushing 82' which may be cemented into the case, but affords the resilience to permit vibration of the socket with its stylus. A similar bushing 30 83' similarly applied excludes particles from about set screw 83. Gasket 104 protects the opening for adjustment screw 102 and celluloid window 110' guards the scanner opening.

35 The correct or balanced position of the armature can readily be determined audibly by sharply tapping the stylus S with the finger nail first in one direction, then in the opposite direction in its gudgeon bearings 87 and continuing the adjustment of the screw 102 until the volume of sound emitted is equal for both 40 directions of displacement. The spring 105 about the screw aids to maintain the damper capsule in any position of setting and prevents idle manipulation unaided by a screw driver or coin.

45 Geometrical centering of the armature should in general approximate magnetic balance thereof. It is due to the irregularities in the construction or magnetic reluctance of the 50 pole pieces etc. that geometrical centering does not in practice afford magnetic balance. Accordingly while the scanner may be used as a primary means for ascertaining approximate calibration of the unit, it is employed 55 preferably only as a preliminary aid to the audible balancing method above described.

60 The position of the rubber damper with respect to the armature remains the same for all adjustment settings. At all times the rubber damper snugly engages both faces of the armature vane and responds uniformly during playing resiliently to oppose vibration of the armature to either side from neutral.

65 It will thus be seen that there is herein de-

scribed apparatus in which the several features of this invention are embodied, and which apparatus in its action attains the various objects of the invention and is well suited to meet the requirements of practical 70 use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent is:

1. An electric phonograph reproducer comprising pole pieces, an armature having a pivotal mount and including a vane substantially in the plane of the pivoting axis, extending between and protruding beyond the pole pieces, non-magnetic means coacting with opposite faces of the protruding armature vane and resisting the movement of the latter, a rigid carrier therefor and manual means accessible from the exterior of said reproducer and coacting said carrier for determining the setting of said non-magnetic means and of said armature relative to said pole pieces.

2. In an electric phonograph reproducer, the combination of a casing, pole pieces therein, a stylus-carrying armature extending between said pole pieces, resilient means for restraining the movement of said armature from one to the other pole, and manual operating means accessible from the exterior of said casing for bodily moving said resilient means to adjust the position of the armature.

3. An electric phonograph reproducer of the type comprising a casing having pole pieces therein, and stylus-carrying armature pivoted in said casing, having non-metallic resilient restraining means coacting with a part of said armature, a holder for said resilient means, and manual means accessible from the exterior of said case for adjusting the position of said holder.

4. In an electric phonograph reproducer, the combination of magnetic pole pieces, an armature having a pivot mount adjacent thereto and having a part thereof extending between and adapted to come into close contiguity with surfaces of opposite poles, resilient restraining means for said armature including gum rubber at opposite faces thereof, bracket means mounting said rubber and free of said armature, and manual adjusting means accessible from the exterior of said reproducer, and coacting with said bracket for movement of the latter at will.

5. An electric phonograph reproducer

comprising magnetic pole pieces, an armature extending therebetween, mounting means for said armature governing the movement thereof, resilient restraining means including gum rubber at opposite faces of said armature and beyond the pole pieces, a holder for said restraining means and a setting device protruding from one end of the holder and accessible from the exterior of the operating parts for adjusting the position of said holder.

6. An electric phonograph reproducer comprising magnetic pole pieces, an armature extending therebetween, mounting means for said armature governing the movement thereof, resilient restraining means including gum rubber at opposite faces of said armature and beyond the pole pieces, a holder for said restraining means, and means accessible from the exterior of the reproducer for adjusting the position of said holder in a path of movement substantially parallel to that of said armature.

7. An electric phonograph reproducer comprising a casing, pole pieces therein, an armature having a pivot axis and a vane substantially in the plane of said axis and extending between and in close contiguity to opposite poles, a gum rubber damper engaging opposite faces of said armature beyond said poles, a holder for said damper, and free from said armature, and an adjustment screw accessible from the exterior of said casing having engagement with said holder, for adjusting the same to balance said armature.

8. An electric phonograph reproducer comprising pole pieces, a damper unit, an armature extending between said pole pieces and coacting with said damper unit, means fastening said damper unit with respect to said pole pieces and setting means for adjusting the position of said damper unit while said fastening means remains in fixed position.

9. An electric phonograph reproducer comprising pole pieces, a damper unit mounted upon said pole pieces and beyond the air gap thereof, an armature extending between said pole pieces with its extremity protruding into said damper said unit including a resilient part and a rigid carrier therefor, and means accessible from the exterior and coacting with said carrier for adjusting the position of said damper.

10. An electric phonograph reproducer comprising a metallic capsule including a base piece and a cover defining a cavity therebetween, a piece of gum rubber lodged within said cavity, means for slidably mounting said capsule adjacent the pole pieces and means for effecting adjustment in the position of said capsule.

11. An electric phonograph reproducer comprising a metallic capsule including a

base piece having a socket, a piece of gum rubber lodged within said socket, a cover piece, means slidably mounting said capsule adjacent the pole pieces, and an adjustment screw coacting with said capsule to adjust the position thereof.

12. An electric phonograph reproducer comprising a pair of pole pieces, an armature pivotally mounted therebetween, having an upstanding vane extending beyond the air gap of said pole pieces, a damper unit engaging the protruding end of the armature, said unit comprising a metallic socket, a piece of gum rubber snugly lodged therein, having a longitudinal slit through which the vane extends, means securing said socket to the pole pieces and permitting limited shifting movement thereof, to center or balance the armature and an adjustment screw having engagement with a portion of said socket.

13. An electric phonograph reproducer including a casing, pole pieces therein, an armature movable between said pole pieces, means accessible from the exterior of said casing for positioning said armature, and scanning means comprising a sight aperture in the casing in front of the air gap.

14. An electric phonograph reproducer comprising a casing, pole pieces therein, an armature pivotally mounted between said pole pieces including a vane extending beyond the air gap of the pole pieces, a gum rubber damper unit engaging the opposite faces of the free end of said vane, means whereby the damper unit may be displaced in order to center the armature and a scanning window in the casing opposite the air gap to aid in determining the balanced position of the armature.

15. As an article of manufacture, a damping unit for a magnetic phonograph reproducer, said unit comprising a sheet metal socket piece, a piece of gum rubber therein, a cover piece, elongated screw slots in said socket and cover pieces for slidably securing the unit in position, one of said pieces having an inturned part for engagement with an adjustment screw.

16. An electric phonograph reproducer, comprising a casing, pole pieces therein, an armature extending across the air gap therebetween, a gum rubber damper engaging opposite faces of the armature beyond the air gap, holder means for said damper, manual screw adjustment means accessible from the exterior of said casing for positioning said holder and with it said damper means, and means automatically retaining said damper means against shifting from adjusted position.

17. A phonograph reproducer construction comprising a support, a thrust bearing fixed thereto, a carrying hub sustained on said thrust bearing and having a pivotal

movement thereabout, a horizontal pivot carried by said hub, a reproducer arm bearing on said pivot, a reproducer head at one end of said arm and a counterweight at the other end of said arm.

18. A phonograph reproducer construction comprising a support, a thrust bearing fixed thereto, a carrying hub sustained on said thrust bearing and having a pivotal movement thereabout, a horizontal pivot support carried by said hub, a reproducer arm bearing on said pivot, a reproducer head connected to one end of said arm and a counterweight at the other end of said arm, said hub having a stop integral therewith to limit the pivoting movement of the reproducer head in a downward direction.

19. A phonograph reproducer construction comprising a support, a thrust bearing fixed thereto, a carrying hub sustained on said thrust bearing and having a pivotal movement thereabout, said hub having a horizontal pivot, a reproducer arm bearing on said latter pivot, a reproducer head connected to one end of said arm and a counterweight at the other end of said arm, the upper end of said hub extending upward through an elongated slot in said arm, affording clearance to permit movement of the latter about its horizontal pivot.

20. An electric phonograph reproducer structure including a support base having an upstanding thrust bearing, a hub piece encircling said base and movable about said upstanding thrust bearing and sustained thereon, a horizontal pivot bearing carried by said hub, a reproducer arm pivotally supported on said horizontal bearing and affording clearance for the upper end of said hub, a reproducer head at one end of said arm and a counter-balanced weight at the other end thereof.

21. An electric phonograph reproducer structure including a support base having an upstanding thrust bearing, a hub piece encircling said base and movable about said upstanding thrust bearing and sustained thereon, a horizontal pivot bearing carried by said hub, a reproducer arm pivotally supported on said horizontal bearing and affording clearance for the upper end of said hub, said reproducer arm being of channel shape, straddling said pivot bearing, and means passing through said channel and affixed to said bearing support, and constituting a bearing for said arm.

22. In an electric phonograph reproducer construction, the combination of a support arm, a reproducer head detachably supported rigidly with respect to the length of said arm, electric terminals on said arm displaced from said head support terminal conductors on said head, freely displaceable relative thereto and plugged into the terminals on said arm.

23. In an electric phonograph reproducer, a pivoted arm, electric conductors extending longitudinally thereof, electric sockets at the ends of said conductors on said arm, a reproducer head detachably connected to the extremity of said arm and rigidly with respect to the length thereof and flexible electric conductor terminals adapted to be releasably plugged into said sockets.

24. In an electric phonograph reproducer, a movable arm, a reproducer head having a detachable mechanical connection for securely retaining said head rigid with respect to the length of said arm, electric terminals on said arm and flexible electrical conductors carried by said head beyond the various parts of said head when the latter is mechanically positioned upon said arm, said flexible conductors and adapted to be releasably plugged with respect to said terminals while said head is in position upon said arm.

25. In an electric phonograph reproducer, an arm having a pivot near one end thereof, a reproducer head having a mounting element for firm coaction with the opposite end of said arm to effect a secure mechanical mounting connection, electric terminals at the side of said arm, and flexible conductors carried by said head and having terminals for releasable coaction with the terminals on said arm.

26. In an electric phonograph reproducer, the combination of a channel shaped support arm, an electro-magnetic unit having a bracket with a pilot portion straddled by the end of said arm, a screw in said arm retaining said pilot in place, and a stop screw in said arm retaining said pilot against movement about said first screw.

27. In an electric phonograph reproducer, the combination of a channel shaped support arm, an electro-magnetic unit having a bracket with a pilot portion straddled by the end of said arm, a screw releasably connecting said pilot in place, an insulating sleeve about said screw, leads from the terminals of said unit, clamped against said pilot by said sleeve and sockets on said arm for releasable connections therewith of the extremities of said leads.

28. As an article of manufacture, a support arm for an electric phonograph reproducer, said arm being of channel form and having a longitudinal rib embossed therein, conductors extending longitudinally thereof within the channel at opposite sides of the rib, clamping pieces extending between the sides of the channel and screwed in place to clamp said conductors in position and terminal sockets accommodating the extremities of said conductors.

29. An electric phonograph reproducer, comprising magnetic pole pieces, an armature extending therebetween, mounting means for said armature governing the mov

ment thereof, resilient plastic damper means engaging both sides of said armature, said damper means free from contact with the pole pieces, and means for bodily shifting said damper means in order to dispose said armature in balanced position.

30. An electric phonograph reproducer, comprising magnetic pole pieces, an armature extending therebetween, mounting means for said armature governing the movement thereof, resilient plastic damper means engaging both sides of said armature, said damper means free from contact with the pole pieces, a metallic holder for said damper supported upon said pole pieces, and means accessible from the exterior of the reproducer for adjusting the position of said holder and with it of said damper and armature.

20 31. An electric phonograph reproducer including magnetic pole pieces, an armature, and a resilient block recessed to receive a portion of the armature therein to center the armature, and means to bodily move the block to set the armature, said means including an 25 enclosing capsule for the block and a threaded adjusting screw associated therewith for moving the capsule upon rotation of the screw.
